ATTORNEY

UNITED STATES PATENT OFFICE.

EDWARD G. GERMER, OF ERIE, PENNSYLVANIA.

BOILER-FURNACE.

SPECIFICATION forming part of Letters Patent No. 624,786, dated May 9, 1899.

Application filed June 17, 1898. Serial No. 683,696. (No model.)

To all whom it may concern:

Be it known that I, EDWARD G. GERMER, a citizen of the United States, residing at Erie, in the county of Erie and State of Pennsylvania, have invented certain new and useful Improvements in Boiler-Furnaces; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to improvements in boiler-furnaces; and it consists, substantially, in constructing a series of vertical flues in the sides of the furnace and front of the bridge-wall extending from below the grate-bars upward a short distance above the top of the bed of fuel on the grate-bars and having the fronts thereof provided with narrow slots through which the gases generated in the fuel pass into said flues and are there intermixed with air passing up therethrough from below the grates and pass out of the upper portions of the slots in said flues, so as to be burned at or just above the surface of the bed of fuel on the grate-bars, whereby I am enabled to secure a much larger consumption of these gases than is possible in boiler-furnaces taking their supply of air through the interstices between the grate-bars alone.

The construction and operation of this invention are hereinafter fully set forth and described, and illustrated in the accompanying drawings, in which—

Figure 1 is a vertical section of a boiler-furnace embodying my invention. Fig. 2 is horizontal section of the same on the line xx in Fig. 1, looking in the direction of the arrows. Fig. 3 is an enlarged perspective view of a section of the same, showing the construction thereof. Fig. 4 is a sectional view of a double-boiler furnace substantially on the plane of the line xx in Fig. 1.

In the drawings thus illustrating my invention, A is a boiler, and B a section of the setting thereof, C the bridge-wall, D the fire-box, E the fire-box doors, F the grate-bars, G the ash-pit, and H the ash-pit doors, all of which are of usual construction, except in that I build in the lining of the sides d of the

fire-box D and in the front c of the bridge-wall C a series of vertical flues I, which extend upward from a point a little below the bottoms of the grate-bars F to a point a little above the top of the bed of fuel J on the grate-bars F. In the fronts of these flues are narrow vertical slots I', which extend the entire length of the flues I, and at the lower ends of the flues I there are inclined openings I² into the ash-pit G, through which any ashes passing into the flues I through the slots I' therein pass down into the ash-pit G. The tops of the flues I and the slots I' are closed, so that the slots I' are the only communication with the flues I, except the inclined openings I² at the lower ends thereof, as is clearly illustrated in the enlarged Fig. 3. These flues and the slots in the fronts thereof I preferably make of fire-brick molded in the proper shape therefor, so as to be laid up, as illustrated in Fig. 3. I can, however, make the flues of metal and set them in the walls of the fire-box, using ordinary fire-brick and building the metal flues into the walls of the fire-box. I prefer, however, to make them of brick molded to the proper shape and laid up as illustrated in Fig. 3.

In operation air passes up from the ash-pit through the flues I, and the gases from the coal being burned also passes into the flues I through the slots I', and as the gases and air intermixed pass out of the upper parts of the slots I' over the top of the coal they are burned, which flame also assists to consume the remaining gases arising from the top of the coal through the surplus air passing up through the flues I and out over the surface of the coal.

In Fig. 4 I show a fire-box with a central longitudinal wall, which only extends up far enough to contain the flues I and which is adapted for use in wide fire-boxes where there is not enough air supplied through the flues in the sides of the fire-box and front of the bridge-wall.

Having thus shown and described my invention, what I claim as new, and desire to secure by Letters Patent of the United States, is—

1. The combination in a boiler-furnace, of side walls having a series of vertical flues therein extending from below the grate-bars

thereof to a point somewhat above the top of the coal on the grate-bars, said flues having narrow vertical slots in the fronts thereof extending into said flues through their entire length, substantially as and for the purpose set forth.

2. The combination in a boiler-furnace, of side walls having a series of vertical flues therein extending from below the grate-bars thereof to a point somewhat above the top of the coal on the grate-bars, said flues having

narrow vertical slots in the fronts thereof extending into said flues throughout their entire length, with a bridge-wall having like slotted flues in the front thereof, substantially as and for the purpose set forth. 15

In testimony whereof I affix my signature in presence of two witnesses.

EDWARD G. GERMER.
